PACKING CYLINDER SLIDE SHEET

William H. Fort, Dayton, Ohio, assignor of one-half to Homer L. Bishop and Earl E. Stansell, doing business as Bishop-Stansell Company, West Carrollton, Ohio

Application February 5, 1948, Serial No. 6,540

16 Claims. (Cl. 101—401.3)

1

This invention relates to the printing art and more particularly to the packing sheets used on the packing cylinder so as to prolong the life of the printing plate.

In rotary printing presses the peripheral speed of the printing surface of the printing plate is substantially the same as the peripheral speed of the web or paper receiving the impression, which web or paper is fed through printing position into contact with the packing cylinder. The ideal situation would be the same peripheral speed of the printing surface of the printing plate as the speed of the web fed by the packing cylinder. This situation, however, cannot exist for the reason that the printing surface of the printing plate does not form a true cylindrical surface. Some portions of the printing plate are recessed and others may project outwardly in order to obtain the proper gradation of shading.

In order to obtain the desired emphasis between high light areas and shaded areas in the reproduction of an electrotype, the electrotypes are face-treated, as for example, by the use of make-ready mats shown and described in the Bishop Patent No. 2,256,921 issued September 23, 1941, for Make-ready. In spite of the fact that the difference in diameter of various portions of the printing surface of the electrotype is not very great, it is sufficient to cause the peripheral speed of various portions of the electrotype to differ. In other words, the portions of the printing surface of the electrotype that have the greatest diameter travel at the highest speed. Furthermore, these portions of the electrotype are the portions that press hardest against the surface of the web being printed. These portions of the electrotype projecting outwardly, so as to give the greatest shock while printing, travel faster than the average velocity of the printing surface of the electrotype and faster than the peripheral speed of the packing cylinder. As a consequence, if the web is not permitted to slip on the packing cylinder, but must travel with the packing cylinder, there will be a slight slippage between the projecting portions of the electrotype and the web. This results in a rather rapid wear of these portions of the electrotype.

Due to the fact that the surface of the electrotype carries ink, it can readily be seen that it would be a comparatively easy matter for a slight slippage to take place between the electrotype and the web, in that the ink functions in part as a lubricant. However, the pigments in the ink may also function as an abrasive material, tending to grind down the projecting sur-

2

faces of the electrotype if any slippage takes place.

An object of this invention is to provide packing material on the packing cylinder that permits the web to travel at any one instant of time at the same velocity as the printing surface in contact with the web.

Another object of this invention is to provide packing material for a packing cylinder that consists of two sheets of packing material, one of

10 which is mounted on the packing cylinder in the usual packing position, the other overlying the first sheet is mounted so as to permit yielding or sliding movement relative to the tight sheet to permit slippage between the two sheets, thereby permitting the web receiving the impression contacting the yieldable sheet to travel at the same velocity as the velocity of the printing surface contacting the web. In other words, the yieldable sheet permits the velocity of the web to adjust itself to the velocity of the printing surface of the printing plate.

Another object of this invention is to provide a floating support on the packing cylinder, such 25 that the resistance to movement of the web upon the packing cylinder is less than the resistance to movement between the web and the printing surface in contact with the web so as to cause the web to move with the printing surface.

Another object of this invention is to provide a 30 floating sheet having unrestrained limited movements on the packing cylinder.

Another object of this invention is to provide a 35 packing sheet for the packing cylinder, which packing sheet rests upon a lubricant.

Other objects and advantages reside in the 40 construction of parts, the combination thereof and the mode of operation, as will become more apparent from the following description.

Referring to the drawings, Figure 1 shows a 45 cross sectional view of the packing cylinder having a floating support mounted thereon underlying a printing cylinder shown schematically for the purpose of illustration.

Figure 2 is a perspective view of a floating support having parts broken away.

Figure 3 is a cross sectional view of the floating support shown in Figure 2.

Figure 4 discloses a modification, with parts 50 broken away.

Figure 5 is a perspective view similar to Figure 4, showing the rubber band in position for holding down the end of the floating sheet.

Figure 6 is a longitudinal cross sectional view, 55 substantially on the line 6—6 of Figure 5.

Figure 7 is a longitudinal cross sectional view of another modification.

In the drawings, the reference character 10 indicates a packing cylinder mounted upon a shaft 12 in a printing press, not shown. Adjacent the packing cylinder 10 are found one or more printing cylinders 14, only one of which has been shown. The circumference of the packing cylinder is an even multiple of the circumference of the printing cylinder, so that the printing cylinder makes one, two, three or four revolutions for each revolution of the packing cylinder, depending entirely upon their relative sizes. The packing cylinder contains one or more slots 16, only one of which has been shown in Figure 1. The slot 16 terminates in a cylindrical recess 18, having mounted therein a shaft 20. This shaft 20 is provided with a notch into which is seated a clamping bar 22. This clamping bar 22 cooperates with a shoulder 24 to clamp a flange 26 of the packing material, consisting of the sheets 28 and 30.

As may best be seen by referring to Figures 2 and 3, the sheet 28 is provided with a transverse slot 32. The sheet 30 is provided with a tapered end 34 that extends through the slot 32. The end 34a of the sheet 30 extends under the sheet 28. The sheet 28 is provided with a tapered end 36 that is positioned in the slot in the shaft 40 mounted in a cylindrical recess 42 in the packing cylinder 10. The shaft 40 may be rotated, so as to tension the sheet 28, causing the sheet 28 to lie flat against the surface of the packing cylinder in a taut manner. Thus, both ends of the sheet 28 are clamped in position, one by the head clamp including the bar 22, the other by the tail or rear clamp including the slotted shaft 40. The sheet 30 may be referred to as a floating sheet, in that it is not tensioned and is permitted to have a limited circumferential movement. This movement may be quite small, on the order of a few thousandths of an inch.

The web 50, shown schematically, rests upon the floating sheet 30 when passing under the printing cylinder 14. Due to the fact that the floating sheet 30 is not tensioned, it readily slides upon the sheet 28, so that whenever the peripheral speed of the contacting printing surfaces differs from the peripheral speed of the packing cylinder during the period of time that the sock is applied to the printing area in contact with the web, the floating sheet allows the web to move with the printing plate and at the same velocity, thereby reducing wear on the projecting portions of the electrotype while in printing position.

In order to aid the floating movement of the sheet 30 upon the sheet 28, the surface of the sheet 28 may be coated with powdered graphite functioning as a lubricant for the sheet 30. The floating sheet 30 relieves some of the strain on both the head and tail clamps, in that the floating sheet absorbs the shock caused by variable peripheral speeds of the printing surfaces. This has been accomplished without sacrificing upon the hardness of the packing. In spite of the fact that the relative movement may be on the order of a few thousandths of an inch, it has been found that electrotypes last much longer when a floating sheet is positioned between the web and the sheet 28 tensioned on the packing cylinder. Although only one packing sheet has been shown on the packing cylinder 10, there are usually as many packing sheets as the ratio

of the circumference of the packing cylinder to the circumference of the printing cylinder.

In the event the sheet 30 is too tight, it will gradually loosen, in that the tab or tongue underlying the portion of the packing sheet 28 will slip out sufficiently to provide the necessary slack. On the other hand, if the sheet 30 is too loose, an additional portion of the sheet may be gradually forced through the slot 32. The flanges 26 of the sheets 28 and 30 are carefully cemented together, so that the one end of both sheets will be rigidly held in position.

Instead of using the slot 32, a sheet 60, shown in Figures 4, 5 and 6, may be mounted upon the packing cylinder. Overlying the sheet 60 is a floating sheet 62. Both the sheets 60 and 62 are provided with flanges cemented together and cooperating to form a flange 64 adapted to be clamped in position. The sheet 62 is shorter than the sheet 60. The free end 66 of the sheet 62 preferably projects into a loop of a rubber band 70, loosely holding the end of the sheet 62 in position. The thickness of the rubber band 70 and the thickness of the sheets have been greatly exaggerated for the sake of clarity. The rubber band 70 is positioned in such a manner that the rubber band is located in the margin of the printing plate, so that the thickness of the rubber band will have no direct influence upon the printed matter.

The function of the rubber band is to hold the trailing end of the floating sheet against the packing cylinder so as to prevent the trailing end from whipping outwardly due to centrifugal force when the floating sheet is out of contact with the web and to hold the floating sheet in position when preparing the printing press for another run.

In this modification, as well as the preferred modification, the top sheet 62 is free to have limited movement in any direction, in that it is not tensioned upon a roughened surface of a packing cylinder, but instead, is mounted in contact with the smooth surface of the underlying sheet.

Referring to the modification disclosed in Figure 7, the bottom sheet 80 corresponds to the sheet 60. The top sheet 82 has a downwardly projecting flange attached to a like flange of sheet 80, the two flanges cooperating to form a clamping flange 84, adapted to be clamped into position on the packing cylinder. The portion 86 along the end of the sheet 82 is folded under the sheet 82 and is cemented to the underlying sheet 80, the cement terminating in short spaced relation from the fold. This is to permit the sheet 82 to function as a floating sheet, in that it may have limited circumferential movement with respect to the underlying sheet 80, to thereby permit the web to have limited relative movement with respect to the packing sheet 80. Again, a suitable lubricant, such as graphite, soapstone, talc, wax or grease, may be used, either between the sheets 60 and 62 or 80 and 82.

Instead of using a packing assembly including two sheets, that is, a base sheet and a superimposed floating sheet, a single sheet may be used having the leading edge rigidly clamped in the head clamp and the trailing end held in the tail clamp, the tail clamp being resiliently urged into tightening position by a torsional spring similar to a spring used in a window shade, which spring yields to permit the base sheet to slide on the packing cylinder whenever the contacting printing surface of the printing cylinder travels at a

5

higher speed than the peripheral speed of the packing cylinder, to thereby permit the web to travel with the contacting surface of the printing plate, rather than to cause a slippage between the plate and the web.

Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described my invention, I claim:

1. A packing sheet assembly for use on a packing cylinder of a printing press, said packing cylinder being provided with a head clamp and a tail clamp, said packing sheet assembly including a base sheet having a flange adapted to be clamped in the head clamp of the packing cylinder, said base sheet having a tapered trailing end adapted to be clamped in the tail clamp of the packing cylinder, a traveling sheet overlying at least a portion of the base sheet, said traveling sheet having a flange extending in parallel relation to the flange of the base sheet and clamped in the head clamp, the length of said traveling sheet being less than the length of the base sheet, the thickness of the packing sheet throughout the usable exposed portion on the packing cylinder being substantially constant, means for releasably securing the trailing end of the second sheet to the base sheet so as to permit limited movement of the second sheet with respect to the base sheet.

2. A packing sheet assembly for use on a packing cylinder of a printing press having a printing cylinder, said packing cylinder being provided with a head clamp and a tail clamp, said packing sheet assembly including a base sheet having a flange adapted to be clamped in the head clamp of the packing cylinder, said base sheet having a tapered trailing end adapted to be clamped in the tail clamp of the packing cylinder, said base sheet having a transverse slot near the tail end thereof, a floating sheet overlying a portion of the base sheet, said floating sheet having a flange extending in parallel relation to the flange of the base sheet and clamped in the head clamp, the trailing end of the floating sheet projecting through the transverse slot in the base sheet so as to have a portion underlying the tail portion of the base sheet, the portion of the floating sheet located between the head clamp and the slot being provided with a slack so as to permit a limited movement to accommodate variations in the peripheral speed of the printing surface of the printing cylinder.

3. A packing sheet assembly for use on a packing cylinder of a printing press having a printing cylinder, said packing cylinder being provided with a head clamp and a tail clamp, said packing sheet assembly including a base sheet having a flange adapted to be clamped in the head clamp of the packing cylinder, said base sheet having a tapered trailing end adapted to be clamped in the tail clamp of the packing cylinder, the main body of the base sheet being curved between the flange and the tapered trailing end, and a floating sheet overlying the base sheet, said floating sheet having one end thereof fixedly attached to the base sheet and the other end thereof loosely held on the curved portion of the base sheet, providing a slack portion be-

6

tween the ends of the floating sheet so as to permit free movement of the portion of the floating sheet located between the ends thereof.

4. A packing sheet assembly for use on a packing cylinder of a printing press having a printing cylinder, said packing cylinder being provided with a head clamp and a tail clamp, said packing sheet assembly including a base sheet having a flange adapted to be clamped in the head clamp of the packing cylinder, said base sheet having a tapered trailing end adapted to be clamped in the tail clamp of the packing cylinder, a floating sheet overlying the base sheet, said floating sheet having one end thereof fixedly attached to the base sheet and the other end thereof loosely held on the base sheet providing a slack portion between the ends of the floating sheet so as to permit free movement of the portion of the floating sheet located between the ends thereof, and a lubricant interposed between the base sheet and the floating sheet to permit the floating sheet to shift relative to the base sheet.

5. A packing sheet assembly for use on a packing cylinder of a printing press having a printing cylinder, said packing cylinder being provided with a head clamp and a tail clamp, said packing sheet assembly including a base sheet having a flange adapted to be clamped in the head clamp of the packing cylinder, said base sheet having a tapered trailing end adapted to be clamped in the tail clamp of the packing cylinder, a floating sheet overlying the base sheet, said floating sheet having one end thereof fixedly attached to the base sheet and the other end thereof loosely held on the base sheet providing a slack portion between the ends of the floating sheet so as to permit free movement of the portion of the floating sheet located between the ends thereof, and finely powdered graphite interposed between the base sheet and the floating sheet functioning as a lubricant so as to permit the floating sheet to easily slide upon the base sheet.

6. A packing cylinder assembly for use in a printing press such as a multi-color printing press provided with printing cylinders, said packing cylinder assembly including a packing cylinder, a packing sheet assembly including a base sheet, means for removably attaching the base sheet to the packing cylinder, the main body of the base sheet having substantially the same curvature as the curvature of the packing cylinder, a floating sheet, means for securing one end of the floating sheet adjacent one end of the base sheet, means for releasably attaching the other end of the floating sheet to the base sheet near the opposite end thereof, the floating sheet having a curvature corresponding to the curvature of the main body of the base sheet, there being a slack in the curved portion of the floating sheet between the attached ends thereof so as to permit a limited movement to accommodate variations in the peripheral speed of the printing surface of the printing cylinder.

7. A packing cylinder assembly for use in a printing press such as a multi-color printing press provided with a printing cylinder, said packing cylinder assembly including a packing cylinder, a packing sheet assembly including a base sheet, means for removably attaching the base sheet to the packing cylinder, a floating sheet, means for securing one end of the floating sheet adjacent one end of the base sheet, means for releasably attaching the other end of the

floating sheet to the base sheet near the opposite end thereof, there being a slack in the floating sheet between the attached ends thereof so as to permit a limited movement, and a lubricant interposed between the slack portion of the floating sheet and the base sheet.

8. A packing cylinder assembly for use in a printing press such as a multi-color printing press provided with a printing cylinder, said packing cylinder assembly including a packing cylinder, a packing sheet assembly including a base sheet, means for removably attaching the base sheet to the packing cylinder, a floating sheet, means for securing one end of the floating sheet adjacent one end of the base sheet, means for releasably attaching the other end of the floating sheet to the base sheet near the opposite end thereof, there being a slack in the floating sheet between the attached ends thereof so as to permit a limited movement, and finely powdered graphite interposed between the slack portion of the floating sheet and the base sheet to provide a lubricant for the floating sheet so as to permit a limited movement thereof to accommodate variations in the peripheral speed of the printing surface of the printing cylinder.

9. A packing sheet assembly for use on a packing cylinder of a printing press having a printing cylinder, said packing sheet assembly including a base sheet attached to the periphery of the packing cylinder in a taut position, a floating sheet overlying the base sheet, means for fixedly attaching one end of the floating sheet to the base sheet, and means for releasably attaching the other end of the floating sheet to the opposite end of the base sheet, said floating sheet having a slack portion between the ends thereof so as to permit free movement of the slack portion to accommodate variations in the peripheral speed of the printing surface of the printing cylinder.

10. A packing sheet assembly for use on a packing cylinder of a printing press having a printing cylinder, said packing sheet assembly including a base sheet, means for attaching the ends of the base sheet in a taut relation upon the periphery of the packing cylinder, the main body of the base sheet having a curvature substantially equal to the curvature of the packing cylinder, a floating sheet overlying the base sheet, the floating sheet having a curvature corresponding to the curvature of the main body of the base sheet, means for fixedly attaching one end of the floating sheet to one end of the base sheet, means for releasably holding the other end of the floating sheet to the opposite end of the base sheet, said floating sheet having a slack portion between the ends thereof so as to permit free movement of the slack portion to accommodate variations in the peripheral speed of the printing surface of the printing cylinder.

11. A packing sheet assembly for use on a packing cylinder of a printing press having a printing cylinder, said packing sheet assembly including a base sheet attached to the periphery of the packing cylinder in a taut position, a floating sheet overlying the base sheet, means for fixedly attaching one end of the floating sheet to the base sheet, means for releasably holding the other end of the floating sheet to the opposite end of the base sheet, said floating sheet having a slack portion between the ends thereof, and a lubricant interposed between the slack portion of the floating sheet and the base sheet so as to

permit free movement of the slack portion to accommodate variations in the peripheral speed of the printing surface of the printing cylinder.

12. A packing sheet assembly for use on a packing cylinder of a printing press having a printing cylinder, said packing sheet assembly including a base sheet attached to the periphery of the packing cylinder in a taut position, a floating sheet overlying the base sheet, means for fixedly attaching one end of the floating sheet to the base sheet, means for releasably holding the other end of the floating sheet to the opposite end of the base sheet, said floating sheet having a slack portion between the ends thereof, and finely powdered graphite interposed between the slack portion of the floating sheet and the base sheet to provide a lubricant for the floating sheet so as to permit a limited movement thereof to accommodate variations in the peripheral speed of the printing surface of the printing cylinder.

13. A packing sheet assembly for use on a packing cylinder of a printing press having a printing cylinder, said packing sheet assembly including a base sheet, means for attaching the ends of the base sheet in a taut relation upon the periphery of the packing cylinder, a floating sheet overlying the base sheet, means for fixedly attaching one end of the floating sheet to one end of the base sheet, means for releasably holding the other end of the floating sheet to the opposite end of the base sheet, said floating sheet having a slack portion between the ends thereof so as to permit free movement of the slack portion to accommodate variations in the peripheral speed of the printing surface of the printing cylinder, and a lubricant interposed between the slack portion of the floating sheet and the base sheet so as to permit free movement of the slack portion to accommodate variations in the peripheral speed of the printing surface of the printing cylinder.

14. A packing sheet assembly for use on a packing cylinder of a printing press having a printing cylinder, said packing sheet assembly including a base sheet, means for attaching the ends of the base sheet in a taut relation upon the periphery of the packing cylinder, a floating sheet overlying the base sheet, means for fixedly attaching one end of the floating sheet to one end of the base sheet, means for releasably holding the other end of the floating sheet to the opposite end of the base sheet, said floating sheet having a slack portion between the ends thereof so as to permit free movement of the slack portion to accommodate variations in the peripheral speed of the printing surface of the printing cylinder, and finely powdered graphite interposed between the slack portion of the floating sheet and the base sheet to provide a lubricant for the floating sheet so as to permit a limited movement thereof to accommodate variations in the peripheral speed of the printing surface of the printing cylinder.

15. A packing sheet assembly for use on a packing cylinder of a printing press having a printing cylinder, said packing cylinder being provided with a head clamp and a tail clamp, said packing sheet assembly including a base sheet having a flange adapted to be clamped in the head clamp of the packing cylinder, said base sheet having a tapered trailing end adapted to be clamped in the tail clamp of the packing cylinder, and a floating sheet overlying the base sheet, said floating sheet having one end thereof

fixedly attached to the base sheet, and a rubber band encircling the base sheet near the opposite end thereof, the other end of the floating sheet projecting under the rubber band so as to be loosely held on the base sheet providing a slack portion between the ends of the floating sheet to permit free movement of the portion of the floating sheet located between the ends thereof.

16. A packing sheet assembly for use on a packing cylinder of a printing press having a printing cylinder, said packing cylinder being provided with a head clamp and a tail clamp, said packing sheet assembly including a base sheet having a flange adapted to be clamped in the head clamp of the packing cylinder, said base sheet having a tapered trailing end adapted to be clamped in the tail clamp of the packing cylinder, the main body of the base sheet having a curvature substantially equal to the curvature of the packing cylinder, and a floating sheet overlying the base sheet, the floating sheet having a curvature corresponding to the curvature of the main body of the base sheet, said floating sheet having one

end thereof fixedly attached to the base sheet and the other end thereof being folded under the adjacent portion of the floating sheet, and means for cementing the folded portion of the floating sheet to the base sheet so as to provide a slack portion between the ends of the floating sheet to permit free movement of the portion of the floating sheet located between the ends thereof.
